UNITED STATES PATENT OFFICE

ERNEST C. SHAW, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

SETWORKS

Application filed May 18, 1928. Serial No. 278,655.

The present invention relates in general to improvements in the art of sawing logs or the like into lumber, and relates more specifically to improvements in the construction and operation of saw mill set works for properly positioning the logs with respect to the saw while the logs are being cut into lumber.

An object of the invention is to provide various improvements in the details of construction of saw mill set works, whereby the manufacture and operation of such devices is facilitated, and with the aid of which the efficiency is enhanced to a maximum. An other object of the invention is to provide an improved enclosing and supporting structure for power set works, wherein the motion transmitting gearing is effectively protected against damage, and in which the bearings and gearing may be abundantly lubricated. A further object of the invention is to provide an improved set works wherein the parts may be conveniently and accurately machined, and readily assembled and dismantled. Still another object of the invention is to provide improved driving mechanism for power set works or the like. Another object of the invention is to provide an improved ratchet wheel structure especially applicable to power set works. These and other objects and advantages will appear from the following description.

A clear conception of embodiments of the several features of the invention and of the mode of constructing and of operating devices manufactured in accordance therewith, may be had by referring to the drawings accompanying and forming a part of this specification in which like reference characters designate the same or similar parts in the various views.

Fig. 1 is a central vertical section through an improved power set works.

Fig. 2 is a side elevation of the improved power set works.

Fig. 3 is a plan view of the improved power set works and of the driving mechanism thereof, the gage and stop mechanism of the set works having been removed.

Fig. 4 is an elevation of the improved

power set works and of the driving mechanism.

The improved power set works illustrated in the drawings is adapted to be located upon the saw mill carriage in the usual manner, and comprises a column shaft 2, a set shaft 3, a power shaft 4, a driving shaft 5, a driving friction 6, and a receding friction 7, all mounted upon a suitable frame 9 and operatively interconnected as herein-after described. The column shaft 2 is supported in upright position by means of lower and upper bearings 23, 24, respectively, the former of which is formed integral with the central portion of a cup-shaped casing or base 19, and the latter of which is rigidly attached to the upper extremity of a closure cap or upper casing 20. The upper extremity of the column shaft 2 is provided with the usual setting mechanism consisting generally of a ratchet wheel secured to the shaft 2, a gage bracket 29 swingably associated with the bearing 24 and with the shaft 2 and engageable with a home stop 27, and a dial 28 associated with the upper extremity of the shaft 2. The ratchet wheel is of novel construction comprising a hub or core 37 provided with a cylindrical peripheral surface 38 upon which a toothed rim 25 is shrunk. By thus constructing the ratchet wheel, the hub section may be formed of relatively inexpensive material while the toothed rim section may be formed of material capable of effectively resisting wear. This construction also permits convenient replacement of the rim section without necessitating replacement of the hub section.

The lower portion of the column shaft 2 is provided with a bevel gear 15 the toothed portion of which is disposed within the cup-shaped base 19. The portion of the shaft 2 within the closure cap 20 and adjoining the bearing 24 is provided with a thrust collar 36 which engages an inner surface of the cap 20 in order to positively prevent upward movement of the shaft 2.

The gear 15 meshes with bevel pinion 17 secured to the set shaft 3 and located within the cup-shaped base 19. The set shaft 3 is supported in a horizontal bearing 22 formed

in the integral central portion of the base 19, the bearing 23 being likewise formed in this central base portion.

The power shaft 4 also extends into the 5 cup-shaped casing 19 and has its inner end supported in a bearing 39 formed in the central portion of the base 19. A bevel pinion 16 which likewise meshes with the gear 15, is secured to the shaft 4 within the 10 base 19, as shown in Fig. 3.

The bearings 22, 23, 39 are abundantly lubricated by means of an oil carrier disk 32 secured to and rotatable with the shaft 3, and cooperating with a scraper to deliver 15 oil into an annular pocket 33, from which the oil is conducted to the upper bearing 23, and overflows to the lower bearings 22, 39. The several bearings associated with the central portion of the base 19, are additionally 20 lubricated by the oil carried upwardly by the pinions 16, 17 which is squeezed from between the teeth of these pinions by virtue of their engagement with the gear 15.

The cup-shaped base 19 is provided with 25 side openings through which the shafts 3, 4 extend, and is also provided with a top opening through which the column shaft 2 extends. All of these openings are circular in shape, the side openings being provided with 30 annular plane surfaces 31, and the top opening being provided with a similar surface 30, all of which may be readily machined in a boring mill. The cap 20 snugly fits the annular top surface 30, and is machinable to thus coat with the base 19, in an 35 ordinary lathe. The side openings of the base 19 are normally closed by means of end caps 21 having turned surfaces engaging the surfaces 31 of the base, and are provided with additional bearings for the shafts 40 which penetrate the caps, and with stuffing boxes 26 for positively preventing escape of oil from within the base 19 along these bearings. The gears and the shaft bearings are 45 thus completely housed within a dust proof casing, the base 19 of which is supplied with an abundant quantity of oil which may be admitted and removed through normally plugged openings 40, 41 in the cap 20 and base 19, respectively. The openings in the 50 base 19 are however of sufficient size to permit free endwise removal of the adjacent gears therethrough, upon removal of the closure plates.

55 The set shaft 3 is adapted to actuate the log engaging knees, in a well known manner. The power shaft 4 is connected with an idler sprocket mounted on the driving shaft 5, by means of chain gearing 14. The 60 idler sprocket of the chain gearing is secured to one element of a friction clutch 13, the other element of which is positively secured to and is rotatable with the driving shaft 5. The driving shaft 5 is rigidly secured to the 65 driven friction 6, the opposite peripheral

portions of which are drivingly engageable with receding and setting frictions 7, 8 respectively, rotatably mounted upon the main frame 9. The arrangement of elements is such, that the driven friction 6 may be brought into driving engagement with either the receding friction 7 or the setting friction 8, by manipulation of an eccentric 34. The eccentric 34 is shiftable by means of linkage 12 cooperating with an operating lever 18, this operating lever also serving to actuate the setting mechanism associated with the column shaft 2, under certain conditions of operation. The frictions 7, 8 are adapted to be constantly driven by means of a rope drive comprising sheaves 10, 11 and a rope 35 engaging the sheaves. 70 75 80

During normal operation of the apparatus, the operating lever 18 may be manipulated to bring the driven wheel or friction 6 into contact with either the setting friction 8 or with the receding friction 7, both of which are rotated by the cable 35 coacting with the sheaves 10, 11. The relatively high speed rotary motion thus transmitted to the driven shaft 5 is conveyed through the friction clutch 13 and chain drive 14 to the power shaft 4, the speed of which is considerably less than that of the shaft 5 by virtue of the speed reduction attained by the chain drive. The pinion 16 carried by the rotating power shaft 4 causes the bevel gear 15 and hence the column shaft 2, to rotate. The rotary motion of the bevel gear 15 is also transmitted to the pinion 17 carried by the set shaft 3, thereby producing movement of the knees in either forward or reverse direction, depending upon the direction of movement of the lever 18. 90 95 100

During setting, the rotation of the column shaft 2 will continue only until the bracket 29 engages the home stop 27, whereupon further movement of the column shaft 2 and of the set shaft 3 will be positively arrested. The movement of the power shaft 4 and of the chain drive 14 will obviously stop when the column shaft 2 is thus arrested, thereby producing slippage between the elements of the friction clutch 13 and permitting continued rotation of the driven shaft 5 until the lever 18 has been shifted. During receding movement of the mechanism, the pawl carried by the bracket 29 and normally engaging the ratchet wheel, may be released thereby permitting continued recession of the knees until the lever 18 is operated to stop the receding movement. 110 115 120

The cup-shaped base 19 is normally provided with a supply of oil and during rotation of the shaft 3 the carrier disk 35 elevates some of this oil. The elevated oil is removed by the scraper coacting with the side of the disk 32, and this scraper delivers the oil into the annular oil pocket 33 from 125 130

which oil is delivered to the bearings 23, 22, 39 in an obvious manner. The pinions 16, 17 also carry oil from the supply within the base 19 and insure abundant lubrication of the gearing. The oil thus elevated by the pinions after lubricating the gearing, is squeezed from between the coacting teeth of the gearing and further insures abundant lubrication of the central bearings and of the bearings in the closure plates 21. The upper bearing 24 and the thrust bearing afforded by the collar 36, may be readily lubricated from the exterior of the mechanism, thus insuring effective lubrication of all of the elements.

The thrust collar 36 cooperating with the bearing 23, positively prevents endwise displacement of the column shaft 2. By forming the ratchet wheel of two sections, suitable wear resisting material may be employed in the rim portion 25, and the life of the ratchet wheel is thereby prolonged. The rim portion may also be renewed when worn without discarding the hub portion. By forming the base 19 with surfaces of revolution with which the caps 20, 21 coact, the elements may be readily machined so as to insure oil-tight joints, and absolute enclosure of the gearing and protection thereof against entry of objectionable substances, is assured.

In the ordinary set works of this type, a slow speed friction clutch corresponding to the high speed clutch 13 of the present disclosure, is located upon the power shaft 4 which is a relatively slow moving element. By virtue of the relatively slow motion of this power shaft, such location of the clutch is objectionable. The location of the clutch 13 on the relatively high-speed driven shaft 5, as disclosed herein, is advantageous because a multiple disk clutch of relatively small diameter operating at high speed corresponding to that of the shaft 5, may then be used and this clutch will require less pressure per square inch of friction surface to produce effective transmission of the power, than the larger slow speed clutches formerly employed. The smaller high speed clutch is also more sensitive in operation when the bracket 29 strikes the home stop 27 and thereby positively arrests the setting mechanism, thus reducing the shock and avoiding injury to the parts.

The multiple disk clutch 13 is readily adjustable to accommodate varying loads dependent upon the size of the logs being sawed, and substantially constant pressure may be maintained by means of adjustable springs which compensate for wear of the friction surfaces. By locating the clutch 13 on the driving shaft 5, the clutch adjusting mechanism is made more accessible than if the clutch were associated with the shaft 4. The location of the clutch 13 on the shaft 5,

also permits location of the set shaft 3 closer to the carriage timbers than with the clutch disposed on the power shaft. The setting and receding speed of the machine may also be readily altered by removing the sprocket which is keyed to the driven clutch element and by replacing this sprocket by one of different diameter, and such change may be effected without shifting the bearing boxes and with minimum expense and difficulty by virtue of the location of the clutch 13 on the shaft 5.

It will thus be apparent that the present invention provides improvements in power set works whereby the various elements are effectively protected against damage, and wherein the elements may be readily manufactured, assembled and dismantled. The caps 20, 21 are made of sufficient size to permit free endwise removal of the gearing from within the base 19, upon removal of the adjacent caps, and the bearings formed integral with the base 19 insure rigid supporting of the shafts within the enclosure.

It should be understood that it is not desired to limit the invention to the exact details of construction shown and described, for obvious modifications within the scope of the claims may occur to persons skilled in the art.

It is claimed and desired to secure by Letters Patent:

1. In a set works, a base forming an enclosure having side and top openings, a power shaft extending into said enclosure through a side opening, a column shaft extending into said enclosure through a top opening, a set shaft extending into said enclosure through a side opening, integral bearings for said shafts disposed within said enclosure, gears connecting said shafts within said enclosure, closure caps for said openings providing bearings for said shafts on the sides of said gears remote from said integral bearings, and means cooperating with said gears to deliver oil to all of said bearings.

2. In a set works, a base forming an enclosure having side and top openings, a power shaft extending into said enclosure through a side opening, a column shaft extending into said enclosure through a top opening, a set shaft extending into said enclosure through a side opening, integral bearings for said shafts disposed within said enclosure, a train of gears connecting said power shaft with said column shaft and said column shaft with said set shaft, closure caps for said openings providing bearings for said shafts on the sides of said gears remote from said integral bearings, said gears and said shafts being endwise removable from said enclosure through said openings upon removal of said caps, and means associated with one of

said shafts and cooperating with said gears to deliver oil to all of said bearings during rotation of said shaft.

3. In a set works, a base forming an enclosure having side and top openings, a horizontal power shaft extending into said enclosure through a side opening, a vertical column shaft extending into said enclosure through a top opening, a horizontal set shaft extending into said enclosure through a side opening, each of said shafts having its axis disposed perpendicular to the axes of the others, integral bearings for said shafts disposed within said enclosure, a train of bevel gears connecting said power shaft with said column shaft and said column shaft with said set shaft, closure caps for said openings providing bearings for said shafts on the sides of said gears remote from said integral bearings, said gears and said shafts being endwise removable from said enclosure through said openings upon removal of said caps, and means operable by said shafts and cooperable with said gears to deliver oil to all of said bearings.

4. In a set works, a base forming an enclosure having side and top openings, a power shaft extending into said enclosure through a side opening, a column shaft extending into said enclosure through a top opening, a set shaft extending into said enclosure through a side opening, integral bearings disposed centrally within said enclosure and surrounded by an oil basin, gears connecting said shafts within said enclosure and above said basin, closure caps for said openings providing bearings for said shafts on the sides of said gears remote from said integral bearings and adjoining the periphery of said basin, and means associated with one of said shafts and cooperating with said gears to deliver oil from said basin to all of said bearings.

5. In a set works, a base forming an enclosure having side and top openings, a power shaft extending into said enclosure through a side opening, a column shaft extending into said enclosure through a top opening, a set shaft extending through said enclosure through oppositely disposed side openings, each of said shafts having its axis disposed perpendicular to the axes of the others, integral bearings disposed centrally within said enclosure and surrounded by an oil basin, a train of gears connecting said power shaft with said column shaft and said column shaft with said set shaft above said basin, closure caps for said openings cooperating with surfaces of revolution on said base and providing bearings for said shafts on the sides of said gears remote from said integral bearings, and means associated with said set shaft adjacent to said integral bearings and cooperating with said gears to deliver oil from said basin to all

of said bearings during rotation of said shaft.

In testimony whereof, the signature of the inventor is affixed hereto.

ERNEST C. SHAW.
